(57) **CLAIM**

The ornamental design for a handguard stabilizer assembly,
as shown and described.

DESCRIPTION

FIG. 1 is a perspective view of a handguard stabilizer assembly showing my new design;

FIG. 2 is another perspective view of the handguard stabilizer assembly shown in FIG. 1;

FIG. 3 is a front elevational view of the handguard stabilizer assembly shown in FIG. 1;

FIG. 4 is a right side elevational view of the handguard stabilizer assembly shown in FIG. 1;

FIG. 5 is a left side elevational view of the handguard stabilizer assembly shown in FIG. 1;

FIG. 6 is a rear elevational view of the handguard stabilizer assembly shown in FIG. 1;

FIG. 7 is a top plan view of the handguard stabilizer assembly shown in FIG. 1;

FIG. 8 is a bottom plan view of the handguard stabilizer assembly shown in FIG. 1;

FIG. 9 is a perspective view of the handguard stabilizer assembly of FIG. 1 installed on a handguard of an upper receiver group for a firearm; and,

FIG. 10 is another perspective view of the handguard stabilizer assembly and handguard of FIG. 9, wherein the handguard has been removed from the upper receiver group. The broken lines shown in the Figures are included for the purpose of illustrating environment and portions of the handguard stabilizer assembly that form no part of the claimed design.
